UNITED STATES PATENT OFFICE.

SVEND MARTIN MEYER, OF NEW YORK, N. Y., ASSIGNOR TO GEORGE CLINTON BATCHELLER, OF NEW YORK, N. Y.

ELECTRIC CIGAR-LIGHTING APPARATUS.

No. 844,610.

Specification of Letters Patent.

Patented Feb. 19, 1907.

Application filed December 21, 1905. Serial No. 292,853.

To all whom it may concern:

Be it known that I, SVEND MARTIN MEYER, a citizen of the United States, and a resident of the borough of Brooklyn, in the city and State of New York, have invented certain new and useful Improvements in Electric Cigar-Lighting Apparatus, of which the following is a specification.

My improved cigar-lighter embraces a torch constructed with two conducting-rods carrying a body of capillary material adapted to be charged with alcohol or other inflammable liquid and an incandescing coil connecting said rods, one of said rods being connected by wire with one pole of a suitable battery and the other projecting in position to be brought in contact with a conducting-post electrically connected with the other pole of the battery, so as to close an electric circuit through the incandescing coil, and thereby ignite the torch.

In the accompanying drawings, Figure 1 is a perspective view of a cigar-lighting apparatus, illustrating my invention. Fig. 2 is a detached view of the lighting-torch, partly in section. Fig. 3 is a detached view of an incandescing coil and the clips on which its ends are mounted for application to the positive and negative conducting-rods of the torch. Fig. 4 is a perspective view, partly in section, showing the battery-case forming the base of the apparatus open and illustrating the mode of effecting electrical connection of the torch and contact-post with the respective poles of unattached battery-cells, as hereinafter described. Fig. 5 is a detail perspective view of adjacent ends of the battery-cells, showing the connection from the carbon of one cell to the zinc of the other and also a contact-spring which, in the act of placing the cells in the casing, establishes connection with the conducting-wires carried by the several lighting-torches, as hereinafter described. Fig. 6 is a side view of the torch, partly in section, illustrating a modification. Fig. 7 is a detail perspective view, on a larger scale, of the lighting-coil and its attachments shown in Fig. 6, together with adjacent portions of the positive and negative conducting-rods and a capillary wick carried by one of them.

A and A', Fig. 4, represent two cells of a "dry" battery of a common form connected by conducting-wire 3 from the carbon or

positive pole of the cell A to the zinc shell of the cell A'. These cells are contained in a case consisting of a box B, having a partition P and a hinged cover C. On the top of this cover is mounted a rigid metal post 1 for making contact with and closing the circuit through a lighting-torch, such as shown, for example, in Fig. 2 or Fig. 6, as hereinafter described. The contact-post 1 extends through the cover or top C of the casing and is in electric connection with a spring-plate 2, which when the cover is closed presses on the zinc shell of the cell A, so as to make effective electric contact therewith. Customary connection between the cells A A' without attachment to the casing is effected by insulated wire 3, clamped by its ends to the carbon of the cell A and the zinc of the cell A'. On the projecting end of the carbon of the cell A' is clamped a spring-plate 4, which in the act of placing the cells in the casing makes contact with a metal plate 5 within the casing connected with a metal tube 6, extending through the end of the casing for reception of the fixed naked ends of insulated wires 7, attached by their free ends to the handles 8 of lighting-torches. Any desirable number of these lighting-torches and conducting wires or cords may be used. For illustration, I have shown two in Fig. 1. When not in use, the torches are set in vertical sockets 9, fixed on top of the cover C, designed and adapted to contain alcohol or other suitable inflammable liquid. For illustration, I have shown five of the alcohol-sockets. In practice an equal number of torches and alcohol-sockets may of course be employed.

A suitable construction of torch will now be described. Referring to Figs. 2 and 6, the base of the torch-handle 8 is made with a screw-cap 8^a, within which the extremity of the insulated wire 7 is confined by a knot or other means. The extreme end of this wire stripped of insulation is clamped between washers 10 by a nut 11 on the rear end of a conducting-rod 12. For convenience in manipulating the nut 11 the cap 8^a can be freely slipped back on the cord 7. Confining the end of the cord by a knot or other means within the cap prevents any strain of the cord on the connection 10 11 when the parts are connected for use. The conducting-rod 12 extends through the handle 8, projects therefrom to a convenient length, and carries one

extremity of an incandescing coil 13, the other extremity of which is mounted on an insulated metal rod 14, mounted in the front end of the handle 8 and having a projecting point 14^a, which (in operation) is pressed against the contact-post 1, so as to close an electric circuit through the coil 13. This effect signition of the alcohol carried by capillary material 15, Fig. 2, in proximity to the incandescent coil 13. In Fig. 2 this capillary material is shown as a wire coil or web 15, wrapped around the insulated rod 14 in position to be immersed in the alcohol when the torch is at rest in its receiving-socket 9, as shown in Fig. 1.

The mode of mounting the incandescing coil 13 on the torch illustrated in Figs. 2 and 3 is as follows: The ends of the coil are attached to spring-clips 16, such as shown in Fig. 3, adapted to spring over and cling to the respective rods 12 and 14. To protect the coil from injury while detached from the torch, the clips 16 are rigidly connected by a brace or strut 17, which may be of insulating material to prevent short-circuiting or direct conduction between the clips 16 while in use; but before placing the clips in position on the rods it is expedient to sever the brace 17, as shown in Fig. 2, so as to leave the clips 16 free for adjustment each to its own rod 12 or 14. The rods 12 and 14 are provided near their ends with collars 12^a or other suitable stops, against which the clips may be slipped to locate the coil 13 in proper position on the rods. 18 represents a shield-plate beneath the coil 13 to deflect the gas evolved from the alcohol and effect its more ready ignition by the incandescent coil. 19 represents a guard projecting over the end of the rod 12, so as to prevent injury to the coil 13 by accidental straddling of the rods 12 and 14 over the margin of the socket in the act of placing the torch therein.

Figs. 6 and 7 illustrate a modification in the mounting of the incandescing coil and capillary medium in the torch so as to avoid the immersion of the incandescing-coil in the alcohol and so that the coil, being dry, may respond more promptly and freely to the heating effect of the electric current. To this end the capillary medium is formed of a long wick 15^a, of asbestos or other fibrous material, clipped by one edge in a sheet-metal back 14^b, which may constitute the insulated

conducting-rod carrying one end of the coil 13 and terminating in the contact-point 14^a. In Figs. 6 and 7 the coil 13 is shown with hooked ends to be clamped by screws 20 to the respective conducting-rods 12 and 14^b. Fig. 7 shows the clamp-screws 20 turned back and the ends of the coil hooked thereon in readiness for turning down the screws to clamp the hooked ends of the coil beneath their heads.

Having thus described my invention, the following is what I claim as new therein and desire to secure by Letters Patent:

1. In an electric torch, the combination of a pair of relatively insulated conducting-rods, a resistance-coil having spring-clips on its ends adapted to catch over said conducting-rods so as to connect them electrically through said resistance-coil, stops on the rods against which the clips may be slipped to locate the resistance-coil in proper position, a capillary body adjacent to the resistance-coil to carry inflammable liquid to be ignited therefrom and means for connecting the respective conducting-rods with the opposite poles of an electric battery, substantially as described. 80

2. In an electric torch, the combination of a pair of conducting-rods mounted in a suitable handle insulating one from the other, an incandescing coil located near the handle, electrically connecting the conducting-rods 85 and an elongated wick of capillary material extending from near the incandescing coil to the end of the torch remote from the handle whereby inflammable liquid in which the end of the torch is immersed may be conducted to 90 proximity to the incandescing coil so as to be ignited thereby, without immersing the said coil in the liquid, substantially as explained.

3. In an electric torch, the combination of a pair of conducting-rods mounted in a suitable handle insulating one from the other, a detachable incandescing coil adapted to be applied to said conducting-rods to form an electric connection between them and a rigid brace or strut mechanically connecting the 95 mountings in which the ends of the coil are fixed, to protect the coil from distortion and injury before application to the conducting-rods, substantially as described.

SVEND MARTIN MEYER.
